UNITED STATES PATENT OFFICE

FRANK J. EVANS, OF SPOKANE, WASHINGTON.

RAIL-JOINT.

1,161,120.

Specification of Letters Patent. Patented Nov. 23, 1915.

Application filed July 22, 1915. Serial No. 41,363.

To all whom it may concern:

Be it known that I, FRANK J. EVANS, a citizen of the United States, residing at Spokane, in the county of Spokane and 5 State of Washington, have invented certain new and useful Improvements in Rail-Joints, of which the following is a specification, reference being had therein to the accompanying drawings.

10 This invention relates to rail joints, and has special reference to joints which are so constructed as to be readily applied to the abutting ends of two rails for efficiently connecting the rails together and preventing 15 the same from sagging when a train passes thereover.

Another object of this invention is the production of a rail joint which is constructed so as to provide a plurality of side plates 20 which are secured to a base plate, these plates being so constructed as to efficiently engage each other for fitting upon the abutting ends of a rail for reinforcing and connecting the ends of the rails and at the 25 same time reinforcing each other.

Another object of this invention is the production of a rail joint wherein the base plate is provided with simple and efficient means for centering the side plates, whereby 30 the device may be easily assembled for connecting the two ends of two rails when so desired.

With these and other objects in view, this invention consists of certain novel combinations, constructions, and arrangements of 35 parts as will be hereinafter fully described and claimed.

In the accompanying drawings: Figure 1 is a side elevation of the rail joint as constructed in accordance with this invention. Fig. 2 is a top plan view of the rail joint. Fig. 3 is a section taken on the line 3—3 of Fig. 2, looking in the direction of the arrows. Fig. 4 is a section taken on the line 4—4 of Fig. 2. Fig. 5 is a section taken on the line 5—5 of Fig. 3, looking in the direction of the arrows, the rails being removed. Fig. 6 is a longitudinal section through the 50 assembled device, illustrating the manner in which the same is mounted upon the rails, portions of the rails being shown in elevation. Fig. 7 is a detailed perspective view of one of the side plates. Fig. 8 is a detailed perspective view of the connecting bar.

55 Referring to the accompanying drawings by numerals it will be seen that the base

plate 1 is constructed so as to form an elongated body which is provided with a plurality of apertures 2, through which the spikes 3 are adapted to pass. The ends of the rails 4 are adapted to be positioned upon this plate 1 so as to allow the heads of the spikes 3 to pass through the apertures 2 and engage the lower portions of the rails 4, as clearly shown in Fig. 1. It is, of course, 60 obvious that the base plate 1 is of sufficient length to rest upon a plurality of the ties 5, and, therefore, this base plate 1 will assist in preventing the ends of the rails 4 from sagging when a train passes over the rails. 65 The centering ribs 6 are formed integral upon the upper surface of the base plate 1, and in parallel spaced relation to each other, as clearly shown in Figs. 4 and 5. The end portions of the rails are adapted to be positioned between these ribs 6 so that the rails will be positively held in alinement with each other without imparting any strain whatever to the other securing means used in connection with this invention. It will 70 be noted that the apertures are formed in direct alinement with the inner portions of the ribs 6, as shown in Fig. 5, so that the side edges of the lower portions or base of the rail will fit snugly against the inner portions of the ribs 6 and extend adjacent the 75 apertures 2. The side plates 7 are elongated and of sufficient width to fit snugly between the upper portion of the base of the rail and the lower surface of the tread of the rail 80 so that the plates may fit snugly against the web of the rail, as clearly shown in Fig. 3. These side plates 7 are provided with horizontal openings 8, which are formed so as to register with the openings 9 formed in the 85 rails 4, whereby the bolts 10, having the nuts 11, may pass through the openings 8 and 9, at which time the nuts 11 may be placed thereon so as to positively hold the plates 7 in engagement with the rails, as 90 above set forth. A web 12 extends from the lower outer surface of the plate 7 adjacent its central portion, as shown clearly in Figs. 2 and 3, and upon this web 12 there are formed the depending portions 13 upon 95 which the inwardly extending flanges 14 are formed, thereby forming the plate so as to constitute a one-piece structure. These flanges 14 are provided with the thickened bodies 15 at their central portions in which 100 there are formed the squared pockets 16, which communicate with the openings 17

extending through the depending portions 13 of the flanges 12. It will be noted by referring to Fig. 5 that the side edges of the plate 1 are provided with the notched portions 18, within which the depending portions 13 of the flanges 12 are adapted to fit, so that the side plates will be positively retained from creeping independent of securing means.

10 In order to secure the lower portions of the side plates in engagement with the base plate there is provided a bar which comprises an elongated squared body 19, having the threaded necks 20 formed integral upon the end portions thereof. The body 19 of this bar is adapted to fit upon the lower portion of the base plate 1, as clearly shown in Fig. 4, at which time the ends of the bar 19 will rest within the squared pockets 16 of the bodies 15. This will allow the threaded necks 20 of the body 19 to extend through the openings 17 formed in the depending portions 13 so as to project for a spaced distance therebeyond, thereby providing sufficient space upon which the retaining nuts 21 are threaded, for positively holding the lower portions of the side plates in engagement with the base plate 1. By having the body portion 19 of the bar squared, it will be seen that the bar may fit snugly upon the lower portion of the base plate 1 without having any tendency to rotate, while the fitting of the squared ends of the body 19 within the squared pockets 16, will also assist in retaining the bar against rotation, and, therefore, after the nuts have been threaded upon the necks 20 of the bar, any tendency of the bar to accidentally rotate, which would, of course, displace the nuts, is prevented and consequently after the nuts have been threaded upon the necks 20 they will at all times remain in their correct positions without danger of accidental displacement since any tendency to rotary movement upon the part of the bar is eliminated.

When this device is in operation the plate 1 is positioned upon a plurality of ties 5, as shown in Fig. 6. The ends of the rails 4 may then be placed upon the plate 1, so as to rest between the ribs 6, as shown in Figs. 3 and 4. These ribs will hold the ends of the rails in alinement with each other thereby facilitating the placing of the side plates upon the rails. When the side plates are positioned upon the rails the depending portions 13 will fit within the notches 18 formed in the side edges of the plate 1, at which time the bar 19 may be placed beneath the plate 1 for passing the necks 20 thereof through the openings 17. The nuts 21 may then be threaded upon the necks for holding the side plates against displacement, while the bolts 10 and nuts 11 are adjusted. Therefore, since the ribs 6 will fit upon the side portions of the abutting ends of the

rails, the tendency of lateral movement on the part of the abutting ends of the rails is eliminated.

It will further be seen that when the plates 7 have been placed in engagement with the side portions of the abutting ends of the rails they will also assist the plate 1 in holding the ends of the rails in horizontal alinement, as the train is passing thereover, so as to prevent the abutting ends of the rails from sagging, as is the case with the ordinary fish plates now in use when the train passes over the abutting ends of the rails.

From the foregoing description it will be seen that a very durable and efficient rail joint has been provided which is adapted to fit upon the abutting ends of two rails, and prevent the same from sagging when in operation, while the reinforcing elements hereinbefore set forth, formed of the ribs and the bar will positively hold the side plates in engagement with the base plate thereby preventing the same from becoming loose when in use, and at the same time minimize the strain upon the securing elements of the joint.

What is claimed is:

1. In a rail joint of the class described, the combination of a base plate having notched side edges, side plates fitting upon said base plate, said base plate being adapted to support the abutting ends of two rails so as to allow the side plates to fit upon the side portion of the abutting ends of the rails, means for retaining said side plates in engagement with the rails, said side plates provided with webs extending from their lower side edges, depending portions formed upon the outer portion of said webs and terminating in inwardly extending flanges fitting upon the lower portions of said base plate, said flanges provided with central bodies, said bodies provided with squared pockets, said bodies also provided with openings registering with said pockets, a square bar fitting upon the lower portions of said base plate, the ends of said bar fitting within said squared pockets whereby said bar will be held from rotating when in use, threaded necks formed upon the end portions of said bar and extending from said openings, nuts threaded upon the outer ends of said threaded necks, whereby said depending portions of said webs of said plates will be held within the notched portions of said base plate whereby said plates will be positively held in an assembled position for constituting a support for the abutting ends of two rails.

2. In a rail joint of the class described, the combination of a base plate, side plates fitting upon said base plate, said base plate being adapted to support the abutting ends of two rails so as to allow the side plates to fit upon the side portion of the abutting ends of the rails, means for retaining said

side plates in engagement with the rails, said side plates provided with webs extending from their lower side edges, depending portions formed upon the outer portions of 5 said webs and terminating in inwardly extending flanges fitting upon the lower portions of said base plate, said flanges provided with central bodies having squared pockets, said bodies also provided with openings 10 registering with said pockets, a square bar fitting upon the lower portions of said base plate, the ends of said bar fitting within said squared pockets whereby said bar will be held from accidental rotation, 15 threaded necks formed upon the end portions of said bar and extending from said openings, nuts carried by said necks, whereby said side plates will be held upon said base plate and will be prevented from creeping. 20

3. In a rail joint of the class described, the combination of a base plate, side plates fitting upon said base plate, said base plate being adapted to support the abutting ends 25 of two rails so as to allow the side plates to fit upon the side portion of the abutting ends of the rails, means for retaining said side plates in engagement with the rails, said side plates provided with webs extending from their lower side edges, depending portions 30 formed upon the outer portions of said webs and terminating in inwardly extending flanges fitting upon the lower portions of said base plate, said flanges provided with central bodies having squared pockets, said bodies also provided with openings registering 35 with said pockets, a square bar fitting upon the lower portions of said base plate, the ends of said bar fitting within said squared pockets whereby said bar will be held from accidental rotation, necks formed 40 upon the ends of said bar and extending from said openings, and means removably mounted upon said necks for holding said side plates upon said base plate. 45

4. In a rail joint of the class described, the

combination of a base plate, side plates fitting upon said base plate, said base plate being adapted to support the abutting ends of two rails so as to allow the side plates to fit 50 upon the side portion of the abutting ends of the rails, means for retaining said side plates in engagement with the rails, said side plates provided with webs extending from their lower side edges, depending portions 55 formed upon the outer portions of said webs and terminating in inwardly extending flanges fitting upon the lower portions of said base plate, said flanges provided with central bodies having openings formed 60 therein, a bar fitting upon the lower portions of said base plate and extending from said openings, and means carried by the extending ends of said bar for holding said side plates upon said base plate. 65

5. In a rail joint of the class described, the combination of a base plate, side plates fitting upon said base plate, said base plate being adapted to support the abutting ends of two rails so as to allow the side plates to fit 70 upon the side portion of the abutting ends of the rails, means for retaining said side plates in engagement with the rails, said side plates provided with webs extending from their lower side edges, depending portions 75 formed upon the outer portions of said webs and terminating in inwardly extending flanges fitting upon the lower portions of said base plate, said flanges provided with central bodies, having openings formed 80 therein, a bar fitting upon the lower portions of said base plate and provided with threaded necks extending from said openings, nuts carried by said necks for holding said side plates upon said base plate, and means engaging said bar for holding the same against 85 accidental rotation whereby accidental displacement of said nut is prevented.

In testimony whereof I hereunto affix my signature.

FRANK J. EVANS.
